UNITED STATES PATENT OFFICE.

HENRY J. STUART, OF DERBY, CONNECTICUT, ASSIGNOR TO THE ROBERT N. BASSETT COMPANY, OF DERBY, CONNECTICUT, A CORPORATION OF CONNECTICUT.

TAB END.

1,169,095.

Specification of Letters Patent. Patented Jan. 18, 1916.

Application filed June 10, 1914. Serial No. 844,164.

To all whom it may concern:

Be it known that I, HENRY J. STUART, a citizen of the United States, residing at Derby, New Haven county, State of Connecticut, have invented certain new and useful Improvements in Tab Ends, of which the following is a full, clear, and exact description.

My invention relates to an improved button tab end for hose supporters, the object being to provide a simple and effective means of connection between the button proper and the supporting tape whereby the necessity for sewing is avoided, and whereby no mechanical fastening is needed to insure the effective connection of said parts.

In the drawings Figure 1 is a front elevation relatively enlarged of my improved button tab end. Fig. 2 is a central vertical section.

1 is a button.

2 is a slotted base plate or frame having two transverse slots therein above the button, and one transverse slot therein below the button.

3 is a tape which is secured to the button wholly by frictional engagement, that is to say, without stitches or mechanical fastenings. This engagement is effected by the

manner of threading the tape through the 30 slots. The tape is threaded through the slotted plate as follows: through the uppermost slot from the front to the rear, thence down to and around the lower edge of the plate and up to and through the lowermost 35 slot from the front to the rear, thence up to and again through the uppermost slot from the rear to the front, thence down to and through the intermediate slot from the front to the rear. 40

What I claim is:

In a tab end, a button, a supporting plate having two transverse slots therein above the button and one transverse slot therein below the button, a tape threaded through 45 said slots as follows: through the uppermost slot from the front to the rear, thence down to and around the lower edge of the plate and up to and through the lowermost slot from the front to the rear, thence up 50 to and again through the uppermost slot from the rear to the front, thence down to and through the intermediate slot from the front to the rear.

HENRY J. STUART.
